UNITED STATES PATENT OFFICE

JOE J. ETTINGER, OF WARSAW, INDIANA, ASSIGNOR TO ZIMMER MANUFACTURING COMPANY, OF WARSAW, INDIANA, A CORPORATION

SURGICAL SPLINT

Application filed May 31, 1930. Serial No. 458,031.

The invention relates to surgical splints and particularly to splints for use in the reduction of fractured legs.

In the reduction of fractured legs it is at times necessary to apply pressure to the leg to retain alinement of the sections of the fractured bone and the object of the invention is to provide a novel splint by which any desired pressure may be applied to any part 10 of the leg.

The invention consists of a leg engaging member that is pivotally mounted on a rotatably and adjustably mounted pivot.

The invention is illustrated in the accompanying drawing in which

Figure 1 is a plan view of the pressure splint attached to a leg splint; Fig. 2 an enlarged side elevation of the pressure splint and Fig. 3 a plan view of the pressure splint, the supporting frame being omitted.

Referring to the illustrative embodiment of the invention, 1 represents any of the usual leg splints having the spaced side members 2 which are adapted to receive the human leg between them with the ring 3 encircling the thigh.

The pressure splint comprises a frame 4 and a padded leg engaging member 8 that is adjustably and pivotally carried by the frame. The frame 4 is preferably arch-shaped with the opposite ends thereof bent laterally, inwardly and upwardly, the extremities of the upstanding portions being secured to the attaching members 5 respectively. Each member 5 is formed with a slot 6 adapted to receive either side member 2 of the leg splint and a thumb set screw 7 carried by the member when tightened abuts the said side member and secures said parts together.

The leg engaging member 8 consists of a longitudinally curved plate 9 to the concaved face of which is secured a pad 10. A hollow boss 11 is formed in the center of the opposite or convex side of the plate 9 and

one end of an angular arm 12 is pivoted in said boss. The opposite end of the arm is secured to a collar 13 that is revolvably mounted on a threaded bolt 14 and held thereon by a set screw 15 the inner end of which screw extends into an annular groove 16 formed in the bolt. The arm 12 is somewhat L-shaped so that the plate is eccentric to the bolt 14 and may be swung to any point in 360° about the bolt when the set screw 15 has been loosened. Since the plate is pivoted to the arm it may be rotated thereon to the proper position for engagement with the leg.

The bolt 14 is threaded in a block 17 having a slot 18 therein at one side of the bolt to receive the frame or arch 4. A set screw 19 is carried by the block in such manner that when tightened it firmly holds the frame in the block and at the inner end of the slot 18. A knob 20 is threaded on the bolt 14 and is held against rotation thereon by the lock nut 21. The knob may be secured to the bolt in any suitable manner. The block 17 may be secured to the frame 4 at any point and the padded plate adjusted to the desired point on the leg. By rotating the bolt 14 in proper direction the plate is pressed on the leg with such pressure as may be required.

If two pressure plates are necessary to accomplish alinement of the bone sections they may be mounted on the same frame or arch or upon separate frames according to the nature of the fracture.

It will be noted that the arcuate portion of the frame 4 is longer than the distance between the two securing members 5 so that the ends of said portion project outside the side members 2 of the leg splint 1, thereby permitting of the adjustment of the plate far down on the side of the leg.

What I claim is:

1. A surgical splint comprising an arcuate frame having its opposite ends turned laterally, inwardly and upwardly, attachment members at the upper ends of the upstanding

portions of the frame respectively and a pressure producing member adjustably mounted on the frame, the mounting being adjustable to any point of the frame including points thereon below the attachment members.

- 5 2. A surgical splint comprising an arcuate frame having its opposite ends turned inwardly and upwardly, attaching members at the extremities of the upstanding portions of the frame respectively, a member attachable to the frame at any point thereof, a screw revolvably carried by the member and a pad carrying-plate loosely mounted on the screw.
- 10 10
- 15 In witness whereof I have hereunto subscribed my name.

JOE J. ETTINGER.
